**RECESSED FOUNTAIN AND VANITY UNIT FOR
A SHIP PASSAGEWAY**

Nelson C. Rancorn, Newport News, Va., assignor to Newport News Shipbuilding and Dry Dock Company, Newport News, Va., a corporation of Virginia

Filed Nov. 25, 1960, Ser. No. 62,957

Term of patent 14 years

(Cl. D66—1)

Fig. 1.

Fig. 2.

FIG. 1 is a perspective view of a recessed fountain and vanity unit for a ship passageway, showing my new design; and

FIG. 2 is a sectional view taken along line 2—2 of FIG. 1 looking in the direction of the arrows.

I claim:

The ornamental design for a recessed fountain and vanity unit for a ship passageway, as shown.
